Specification for Design.

Patented Mar. 30, 1915.

Application filed October 22, 1914. Serial No. 868,139. Term of patent 7 years.

To all whom it may concern:

Be it known that I, THEODORE G. STRATER, a citizen of the United States, residing at West Tisbury, county of Dukes, State of Massachusetts, have invented a new, original, and ornamental Design for an Ash-Tray, of which the following is a specification, reference being had to the accompanying drawing, forming part thereof.

In the drawings, Figure 1 is a top plan view of an ash tray illustrating my new design; Fig. 2 is a bottom plan view thereof;

Fig. 3 is a side elevation thereof; and Fig. 4 is a section taken centrally thereof and transverse to the view shown in the other figures.

I claim:

The ornamental design for an ash tray as shown.
